APPARATUS AND METHOD FOR USE IN
FEVER THERAPY

John H. Emerson, Cambridge, Mass.

Application June 11, 1940, Serial No. 339,843

5 Claims. (Cl. 128—373)

This invention relates to a novel method and apparatus for use in fever therapy and more particularly to an improved method utilizing very finely divided fog-like heated water particles.

Fever therapy is used for the treatment of patients suffering from certain types of arthritis, syphilis, gonorrhoea, and other diseases. It consists in raising the patient's temperature to from 103° to 109° F. for periods of time ranging from one-half an hour to as long as twenty hours. The elevated temperature of the patient for the required period of time tends to destroy some, if not all, of certain disease germs and to speed recovery of the patient. The temperatures used and duration of the treatment depends upon the disease being treated and the physical condition of the patient, and they should be prescribed only by a competent physician.

The primary object of the present invention is to provide a fever therapy method and apparatus utilizing very finely divided fog-like heated water particles for raising and maintaining a patient's temperature.

Further objects are the provision of such a method and apparatus which utilizes such fog-like water particles to produce substantially 100% relative humidity in the patient-enclosing chamber, which retains the particles in the chamber without subjecting them to any substantial air currents and an optional method which periodically utilizes finely divided fog-like particles of cooled water.

Another object is the provision of a novel and useful method of fever therapy and novel apparatus for carrying out said method.

Further objects will be apparent from a consideration of the following description and the annexed drawings which exemplify one embodiment of an apparatus which may be used to carry out my method and which has been chosen for the purpose of illustration.

In the drawings:

Fig. 1 is a sectional view of an apparatus for use in carrying out my method, the section being taken on the lines 1—1 of Fig. 5;

Fig. 2 is a top plan view of the apparatus with the cover and patient-receiving tray or pan removed;

Fig. 3 is an end elevational view looking at the foot end of the apparatus;

Fig. 4 is an end elevational view looking at the head end of the apparatus;

Fig. 5 is a section on the line 5—5 of Fig. 1; and

Fig. 6 is a sectional view of one of the humidifiers used in the apparatus.

A frame 10 is mounted upon the wheels 11 so that the apparatus may be moved from place to place as desired. A horizontal water-containing pan 12 (Figs. 1 and 5) is secured adjacent its edges to the frame 10. The pipe 13 and valve 14 afford an outlet through which the water 9 may be drained from the pan 12 and through which fresh water may be supplied to the pan by attaching a hose between the valve 14 and any convenient water tap.

Two humidifiers 15 are supported by the rods 16 which have their outer ends welded or otherwise secured to the strips 17 which in turn are secured to the frame 10.

At the foot end of the apparatus a separate chamber is provided by means of the partition 18 and the pan 19 (Fig. 1) which are secured adjacent their edges to the frame 10. A hinged door 20 (Figs. 1 and 3) affords access to this chamber and a humidifier 21 is mounted therein. A pipe 22 and valve 23 afford a water outlet and inlet to and from the pan 19.

Two heating units 25 (Figs. 1 and 5) extend substantially parallel to the pan 12 and each heating unit is electrically connected with the control box 26 (Figs. 1 and 4) and with a suitable electric outlet for the reception of a cord and plug 27 leading to any convenient source of current such as a wall socket in the room. The control box is provided with suitable switches or controls whereby the current in the heating units 25 may be turned on and off to regulate the temperature of the water in the pan 12.

A pan 28 (Figs. 5 and 1) is supported by the two longitudinally extending members 29 which extend parallel to the sides of the frame and which are welded or otherwise secured to the cross members 30. The ends of the cross members 30 are welded or otherwise secured to the members 17 which in turn are secured to the frame. The pan 28 may be lifted from the supporting members 29 if desired (Figs. 5 and 2). The bottom of the pan slopes toward the orifice 33 and beneath the orifice there is mounted a conduit 34 the lower end of which terminates above a removable basin 35. Any perspiration or other fluids which fall into the pan 28 pass through the orifice 33 to the basin 35 which may be emptied from time to time.

The racks 36 are supported by the pan 28 and the patient reclines upon a rubber covered mattress (not shown) which is supported by these racks. The headrest 37 (Figs. 1, 2 and 4) is adjustably secured to the head end of the frame. A cover 40 is hinged to the frame at 41 (Figs. 1

and 3) and the rods 42 have their upper ends secured to the hinges or to the cover so that said rods move with the cover about the axis of the hinges. A horizontal rod 43 is secured between the lower ends of the rods 42 and a coil spring 44 has one end secured to the rod 43 and the other end secured to the bottom of the pan 12. Thus when the cover is moved upwardly about the axis of the hinges 41 the spring 44 aids its movement and when the cover is returned to the closed position shown in Fig. 1 the spring tends to retard its movement. Removable doors 46 are provided in the sides of the cover for ready access to the patient during treatment. A towel rack or bar 47 is secured to the head end of the cover and is used to support a blanket or towel for providing a closure between the end of the cover and the patient's neck during treatment. The walls of the cover, the door 46, and the frame 10 are insulated as shown in Figs. 1 and 5.

Communication between the patient-enclosing chamber and the chamber at the foot end of the apparatus is provided by the hollow member 50 (Figs. 1 and 2). Communication between the patient-enclosing chamber and the chamber which houses the vaporizers 15 is provided by the space between the edge of the pan 28 and the sides of the frame, as shown in Figs. 5, 2 and 1.

The humidifiers 15 and 21 are each of the construction shown in Fig. 6, which is a vertical section of such a humidifier. Each humidifier comprises a cover 60 provided with outlet perforations 61. The cover 60 is supported on the peripheral flange 62 of the housing 63. A felt cushion 64 is provided between the flange and the cover. The housing 63 is provided with drain openings 65. A flanged cylinder 66 is supported upon legs 67 which are secured to the housing. The cylinder 66 is provided with a plurality of vertical slots 68 and just above the upper end of the slots a horizontal supporting member 69 is secured to the cylinder 66. The electric motor 70 is mounted upon the supporting member 69 and current for operation of the motor is supplied by the cord 71 which runs to the control box 26 (Fig. 1) where a control switch is provided for the motor of each humidifier. The motor is provided with a rotating drive shaft 72 to which the knife-edged disk-shaped member 73 is secured by the set screw 74. A vertical cylinder pump member 75 is secured to the disk 73 and the drive shaft 72. The lower end of the pump member 75 is provided with a cap 76 having a slot 77 which permits water to enter therethrough. An annular groove 78 is provided in the disk 73 and four horizontal tubes 79 connect this groove with the interior of the pump member 75. A mesh screen 80 covers the groove 78. Four or more fan blades 81 are formed beneath the disk 73. The lower end of the pump member 75 is surrounded by a spaced strainer 82 which is secured to the housing 63.

When the motor is operated the disk 73 and the pump 75 are continuously rotated by the motor drive shaft 72. Rotation of the pump causes water to enter the opening 77 in the cap 76 and to rise along the inner wall of the pump until the water reaches the ends of the horizontal tubes 79 through which it passes to fill the groove 78. The water then overflows through the screen 80 to the surface of the rotating disk 73 and flows over the surface of the disk until it reaches the knife blade periphery where it is thrown from the edge of the disk in the form of

very fine fog-like particles which pass through the vertical slots 68. The fan blades 81 create sufficient air circulation to cause the fog-like water particles to pass upwardly through the ports 61. Any moisture which is condensed during the process passes downwardly through the holes 65 and returns to the pan 12 (Fig. 1).

In use of the apparatus for carrying out my novel method, to raise the patient's temperature it is usually necessary to raise the temperature 10 in the patient enclosure or chamber to about 130° F. and to hold it there until the patient's temperature reaches the desired elevation of from 103° to 109° F. The temperature of the 15 enclosure is then lowered to approximately the temperature of the patient and is maintained at that temperature until termination of the treatment.

Before the patient is inserted the heating elements 25 are turned on, raising the temperature 20 of the water in the pan 12 to approximately 130° F. and the motors of the humidifiers 15 are started to test operability of each humidifier.

To insert the patient the cover 40 is moved 25 upwardly about the axis of the hinges and the patient is placed upon the support with his head upon the headrest, the cover is closed and a towel or blanket is arranged to seal the space between the patient's neck and the head end of the cover. The patient is thus secured in an insulated substantially air-tight enclosure.

The humidifiers 15 are then started and they 30 eject very finely divided fog-like particles of water which are heated to approximately 130° F. These fog-like particles float slowly upwardly 35 around the edges of the pan 29 into the patient-enclosing chamber until the atmosphere is saturated therewith. The result is an atmosphere of substantially 100% relative humidity and a 40 temperature of approximately 109° F. After the chamber has been filled with the fog-like water particles there are substantially no air currents in the patient-enclosing chamber and the chamber is filled with what might be described as 45 static fog at a temperature of about 109° F.

When the patient's temperature reaches 103° to 109° F. the temperature of the water in the pan 12 is reduced so that the temperature of the fog in the patient-enclosing chamber will be 50 maintained at substantially the patient's temperature. The use of these finely divided fog-like water particles is of great importance because it permits the use of substantially 100% relative humidity in the patient-enclosing chamber, the use of substantially no air currents therein, and the use of a minimum temperature (103° to 55 130° F.) for raising and maintaining the patient's temperature. Under such conditions it has been found that the patient's skin is heated as little as possible, there is less stimulation to the sweat glands and to the nerve endings and patient exhibits far less restlessness, runs lower pulse rates and there is less likelihood of delirium. Such a 60 method of fever therapy treatment has been found far superior to a method in which water is sprayed directly into the chamber creating air currents necessitating the use of higher temperatures of water to elevate and maintain the patient's temperature and producing less than 65 100% relative humidity.

When patients are in the apparatus for extremely long periods it may be desirable to occasionally give them physical relief from the high temperature. This is done by placing cold 70 water in the pan 19 and running the humidifier

21 for a short period. This humidifier conveys finely divided cold water particles to the patient-enclosing chamber, thereby lowering its temperature.

While I have shown and described one desirable method and one desirable embodiment of apparatus for carrying out the method, it is to be understood that this disclosure is for the purpose of illustration and that various forms of the apparatus may be used and that the substitution of equivalent steps in the process may be made without departing from the spirit and scope of the invention as set forth in the appended claims.

I claim:

1. Method of fever therapy comprising heating a body of water to from 100° to 130° F., breaking up a portion of said water into finely divided fog-like particles, conveying said particles to a chamber in which the patient's body is enclosed to thereby subject the body of the patient to said heated, finely divided fog-like particles, and returning the water which collects on the walls of the patient-enclosing chamber to said body of heated water, whereby the temperature of said chamber is elevated to and maintained at from 100° to 130° F.

2. Method of fever therapy comprising heating a body of water to from 100° to 130° F., breaking up a portion of said water into finely divided fog-like particles, conveying said particles to a chamber in which the patient's body is enclosed to thereby subject the body of the patient to said heated, finely divided fog-like particles, returning the water which collects on the walls of the patient-enclosing chamber to said body of heated water, and collecting moisture which drips from the patient's body to prevent said moisture from returning to said body of heated water, whereby

the temperature of said chamber is elevated to and maintained at from 100° to 130° F.

3. In a fever therapy apparatus having a patient-receiving chamber and a substantially horizontal support in said chamber for supporting the patient's body, the improvement which comprises a tank below said support constructed and arranged to receive and retain water collecting upon and running down the walls of the chamber, and mechanical means constructed and arranged to receive water from said tank and to break it up into finely divided fog-like particles.

4. In fever therapy apparatus having a patient-receiving chamber and a substantially horizontal support in said chamber for holding the patient's body, the improvement which comprises a water tank below said support constructed and arranged to receive and retain water collecting upon and running down the walls of the chamber, electrical means to control the temperature of the water in said tank, and mechanical means constructed and arranged to receive water from said tank and to break it up into finely divided fog-like particles.

5. In fever therapy apparatus having a patient-receiving chamber, a substantially horizontal support in said chamber for holding the patient's body, and a pan below said support constructed and arranged to collect moisture from the patient's body, the improvement which comprises a water tank below said pan constructed and arranged to receive and retain water collecting upon and running down the walls of the chamber, electrical means to control the temperature of the water in said tank, and mechanical means constructed and arranged to receive water from said tank and to break it up into finely divided fog-like particles.

JOHN H. EMERSON.
